UNITED STATES PATENT OFFICE.

CHARLES A. BERKEY, OF HIGHLAND PARK, MICHIGAN.

DESIGN FOR A BADGE, BUTTON, OR EMBLEM.

56,115.

Specification for Design.

Patented Aug. 24, 1920.

Application filed December 15, 1919. Serial No. 345,142. Term of patent 14 years.

To all whom it may concern:

Be it known that I, CHAS. A. BERKEY, a citizen of the United States, residing at Highland Park, in the county of Wayne and State of Michigan, have invented a new, original, and ornamental Design for a Badge, Button, or Emblem, of which the following is a specification, reference being had to the accompanying drawing, forming a part thereof.

The figure is a plan view of a badge, button, or emblem illustrating my new design.

The letters X and C, the words Unity for Service, and the two circles are formed of gold or material having the appearance of gold being yellow in color, the superimposed letters X and C appearing in yellow on a blue ground. The words "Unity for Service" appear on a white ground.

I claim:

The ornamental design for a badge, button, or emblem as shown.

CHAS. A. BERKEY.
